UNITED STATES PATENT OFFICE.

CHARLES F. BURROUGHS, OF EAST ORANGE, NEW JERSEY, ASSIGNOR TO COMPOSITION MACHINERY CORPORATION, OF NEWARK, NEW JERSEY, A CORPORATION OF NEW JERSEY.

MEANS FOR HOLDING IMPRESSION-PLATES UPON HEATER-BEDS.

1,346,876.

Specification of Letters Patent.

Patented July 20, 1920.

Application filed July 15, 1919. Serial No. 310,994.

To all whom it may concern:

Be it known that I, CHARLES F. BURROUGHS, a citizen of the United States, residing at 122 Prospect street, East Orange, 5 county of Essex, and State of New Jersey, have invented certain new and useful Improvements in Means for Holding Impression-Plates upon Heater-Beds, fully described and represented in the following 10 specification and the accompanying drawings, forming a part of the same.

This invention relates to means for securing a series of dies or impression-plates detachably upon a heater-bed so that when 15 used in a press for molding plastic material, which requires the application of heat, the dies may be held upon a plane surface of the heater-bed and readily removed therefrom and other dies secured thereto.

20 In practising the invention, a holder for a series of dies is formed of a flat plate, with a series of perforations adapted each to receive one of a series of dies, the dies being enlarged at one end and fitted to the perforations so that their bases all lie in the same 25 plane and can thus be applied to a flat heater-bed without fitting the dies separately to the bed.

With such construction, the dies are not 30 fastened individually to the heater-bed but are held thereto in their working positions by fastening the holder to the said bed.

Such dies are commonly employed in connection with counterparts or "forces" for 35 compressing the material upon the die, and this invention enables a series of such dies and their counterparts to be mounted in separate holders in exactly corresponding positions, so as to fit accurately upon one 40 another when used in a press.

The invention will be understood by reference to the annexed drawing, in which Figure 1 shows the under side of a die-holder; Fig. 2 is a section of the same on line 2—2 in Fig. 1; and Fig. 3 is a section on 45 line 3—3 in Fig. 1.

Figs. 4, 5 and 6 are drawn upon a scale four times as great as the other figures.

Fig. 4 is a section of two dies adapted to 50 mold a button with the adjacent parts of their holders; Fig. 5 is an edge view of the lower die; and Fig. 6 is an edge view of a circular button molded in the said dies. Fig.

7 is an edge view of a heater-bed with a die-plate held detachably thereto by gibbs.

55

a indicates the plane surface of a heater-bed *b*, and *c* designates a holder consisting of a flat plate having a series of circular perforations *d*. This view shows the under side of the holder which is applied next to the 60 heater-bed, and a circular recess or rabbet *f* is shown in the nearer side of each of the perforations to receive a flange or collar *e* upon one end of the circular die *g*.

The holder-plate presses upon the flanges 65 of all of the dies when secured upon the heater-bed and thus holds them firmly in place. Holes *h* are shown extended through the holder at various points to receive screws *i* having flat heads which are recessed into 70 the plate flush with its surface.

The bodies of the screws are fitted to tap-holes *a'* in the heater-bed, and such screws serve to clamp the holder to the heater-bed, with all the dies in suitable positions upon 75 such bed, to coöperate with a series of counterpart dies *g'* held in a similar holder upon the working face *j* of a suitable "force."

With such construction the working face 80 of the "force" can be flat like the face *a* of the heater-bed and the counterpart dies *g'* held upon the "force" by a holder similar to that shown upon the heater-bed.

Two holes *e'* are shown in the holder of 85 Fig. 1 for inserting steady-pins through the holder into the heater-bed or "force" to set the holder *c'* with the dies in their working positions.

The die *g* is shown formed to shape the 90 under side *k* of a button, and the counterpart die *g'* has an impression adapted to form a hub *l* upon the rear side of the button; but the impressions in the dies are wholly immaterial to this invention, which 95 is adapted to hold dies having any form of recess or impression engraved therein to suitably shape articles of plastic material.

It will be observed that exact register between all the dies in the holder *c* and those 100 in the holder *c'* can be effected by securing the two holders together in the process of manufacture by extending the perforations *d* through the same. Such method obviously makes the perforations agree exactly in the 105 two holders and insures the coincidence of

the two sets of dies when the holders are properly adjusted upon the heater-bed and the "force."

- 5 The perforations *d* through the holder are preferably made circular as apertures of such shape are formed so readily and cheaply by a revolving drill or shaping tool; but the impression in the die may be formed of any possible shape, and the exterior of
 10 the die of any convenient shape provided the perforations of the holder are adapted to receive such dies and to retain them in their working position upon the heater-bed. It will be understood that the perforations of
 15 the holder fit in contact with the dies upon all sides as they encircle the dies in contact with their larger ends.

A modification of the means for retaining the die in the holder is shown in the lower
 20 part of Fig. 2 where the exterior of the die *g*² is shown tapered from the base to the front, and the perforation in the holder correspondingly tapered so that the die is held firmly in the holder when clamped upon the
 25 heater-bed.

The circles *f* drawn in Fig. 1 within the perforations *d* may represent either the shouldered rabbet lettered *f* in Fig. 4, or the taper of the perforation shown in
 30 Fig. 2.

Such taper of the die-body greatly facilitates the insertion of the dies in the perforations of the holder, and where the die is formed with a collar the front end of the
 35 die is preferably tapered as shown at *g*².

Fig. 7 shows a modification of the means for securing the holder and series of dies upon the heater-bed *b*', which avoids the necessity of removing the screws *h* when
 40 it is necessary to remove the dies.

This modification consists of gibbs *m* secured by screws upon the heater-bed near its opposite edges, and fitted to rabbets *n* in opposite edges of the holder-plate.

45 Screws *n*' hold the gibbs upon the heater-bed and when loosened permit the insertion or removal of the holder, and when tightened grip its opposite edges so as to hold it in its working position. Such use of gibbs
 50 is a common expedient and is not claimed herein.

A stop may be provided upon the heater-bed at any point to set the holder in its working position, or steady-pins may be inserted through the holder into the bed, as described for the pins *e*² in Fig. 4.

55 Twenty-eight perforations *b* are shown in the holder in Fig. 1, and the invention is especially applicable for holding the large
 60 number of relatively small dies of the same shape and dimension, but the size and number of the dies is immaterial provided the holder is formed with a plurality of perforations adapted to receive a series of dies and

retain them upon the heater-bed, as described.

65 My invention permits the ready removal of dies from a press when the impressions therein are damaged or worn and it also permits dies having different impressions to be substituted in the same holder, or a different holder substituted to support dies of larger or smaller dimension.

70 It will be understood that the heater-bed is inserted in a suitable press so as to operate the dies in molding the desired article, and such heater-bed may be heated in any desired manner.

75 It is common to make such heater-beds hollow, as shown in Fig. 3, and to circulate a heating fluid therein through an inlet *b*² and an outlet *b*³ shown in Fig. 7, but the heater-bed may be heated by electric or other suitable means as the combination of such means is wholly immaterial to the present invention.

80 Having thus set forth the nature of the invention what is claimed herein is:

1. The combination, with a plurality of similar impression dies, enlarged at one end, 90 of a holder having a series of perforations adapted to receive such dies and to retain them upon a heater-bed.

2. The combination, with a plurality of circular dies each enlarged at one end, of a 95 holder having a series of circular perforations enlarged at one end and proportioned to receive the enlarged end of each die and to press the same upon a heater-bed.

3. The combination, with a plurality of 100 circular dies each having a collar upon one end, of a holder having a series of perforations recessed each in one end and adapted to receive the collars upon the dies and to hold the dies in contact with a heater-bed. 105

4. In a means for securing a series of dies upon a heater-bed, the combination, with a 110 holder having a series of circular perforations, of dies fitted to the said perforations and tapered at one end to readily enter said perforations.

5. The combination, with a heater-bed having a plane surface, of a series of dies adapted to rest upon said surface and a holder having perforations adapted to receive the base of each die and provided with means for securing it upon the heater-bed, and a "force" having a plane surface, a series of counterpart dies adapted to sit upon said surface, a holder having perforations adapted to receive such counterpart dies, and means for securing the said holder upon the "force" with the counterpart dies in register with the dies upon the heater-bed. 115 120 125

In testimony whereof I have hereunto set 125 my hand.

CHARLES F. BURROUGHS.
